UNITED STATES PATENT OFFICE.

WILLIAM DAUGHERTY, OF LAWRENCEVILLE, ILLINOIS, ASSIGNOR OF ONE-HALF TO A. D. SPRINKELL, OF SAME PLACE.

TIRE-SETTER.

SPECIFICATION forming part of Letters Patent No. 660,490, dated October 23, 1900.

Application filed October 2, 1899. Serial No. 732,436. (No model.)

To all whom it may concern:

Be it known that I, WILLIAM DAUGHERTY, a citizen of the United States, residing at Lawrenceville, in the county of Lawrence and State of Illinois, have invented a new and useful Tire-Setting Machine, of which the following is a specification.

My invention relates to tire-setters and spoke-menders, and has for one object to provide an apparatus for mending spokes and setting tires which is cheap, durable, and, above all, efficient.

A further object of my invention is to provide an apparatus which will make a solid metal shoulder in a spoke and which will make a new metal tenon or replace a split spoke without removing the tire or any bolts from the wheel.

Referring to the drawings, Figure 1 shows a wheel and an ordinary stretcher to raise the felly in order to carry out the objects of my invention. Fig. 2 is a perspective view of my mold. Fig. 3 shows a section of the spoke provided with a new metal shoulder. Fig. 4 represents a view of a section of a spoke upon which a metal tenon has been made. Fig. 5 is a view of a section of a split spoke which has been repaired by my device. Fig. 6 shows my device in an operative position.

The same numerals of reference indicate like parts throughout the several figures, in which—

1 represents a stretcher of any description suitable for raising the felly of the wheel, but preferably one having an upper section 2 and an operating-nut 3.

4 indicates my mold, constructed, preferably, of spring-steel bent at 5, each arm being provided with a series of corresponding semicircular bends 6, designed to fit different-sized spokes, said mold having handles 7.

8 represents a small mouth, into which the molten metal is poured.

9 indicates the mended spokes, and 10 indicates the metal.

11 indicates the paper, which is wound around the portion of the spoke to be mended before the mold 4 is applied.

Having thus described the several parts of my invention, its operation is as follows: A

stretcher 1, of any desired construction, is placed between the hub and the felly or rim of the wheel and alongside of the spoke which is to be provided with a new shoulder or tenon. If the former is the object desired, the felly of the wheel is raised until separated from the spoke. Paper or like material is then wound around the broken or worn shoulder, so as to fill up the spaces between the spoke and the mold. The mold is then applied, as shown in Fig. 6, and molten metal is then run into mouth 8 until the space between the felly and the spoke, together with all cracks and crevices, is completely filled, the paper preventing the metal from running out and the mold confining the metal in the desired position. The metal is then allowed to cool, and the paper and mold are taken off, the stretcher is withdrawn, and the felly rests against the newly-made shoulder, as shown in Figs. 1 and 3.

If it is desired to make a new tenon, the stretcher is applied as described, the felly is raised, the broken spoke is sized down, and the paper and mold applied as before. The metal is then poured in, this time filling up the vacant socket in the felly and making a metal ferrule on the spoke, thus forming a complete metal tenon, as shown in Fig. 4.

If it is desired to mend a split spoke, the stretcher is applied, giving free access to spoke, a groove is cut around the split part, the paper and molds are attached around groove, and the metal is then poured in and allowed to cool, thereby creating a solid metal band around the split spoke and filling up all cracks and crevices and rendering the spoke as firm and solid as before being split.

I do not wish to be understood as limiting myself to the exact method and construction herein set forth, but consider myself entitled to any changes or modifications which fall within the spirit and scope of my invention.

Having fully described the several parts and specifically the method of operating my invention, what I claim as new, and desire to secure by Letters Patent of the United States, is—

1. The herein-described improvement in the art of repairing wheels and tightening

spokes and tires, which consists in forcing a portion of the felly more or less from the end of the spoke, in applying paper or like material around the spoke, in applying a mold around such paper and the spoke, and in pouring molten metal into the mold to appropriately fill the space between the felly and the spoke, substantially as described.

2. The herein-described improvement in the art of repairing wheels and tightening the spokes and tire, which consists in forcing a portion of the felly more or less from the end of the spoke, in dressing or shaping the spoke, in applying paper or like material around the spoke, in applying a mold around such paper and the spoke, and in pouring molten metal into the mold to appropriately fill the space

between the felly and the spoke, substantially as described.

3. The herein-described improvement in the art of repairing wheels and tightening the spokes and tire, which consists in forcing a portion of the felly more or less from the end of the spoke, in cutting a groove around the spoke, in applying paper or like material around the spoke, in applying a mold around such paper and the spoke, and in pouring molten metal into the mold, substantially as described.

WM. DAUGHERTY. [L. S.]
